UNITED STATES PATENT OFFICE.

JAMES BAXTER AND DAVID BAXTER, OF CHICAGO, ILLINOIS.

FILLING-MACHINE.

SPECIFICATION forming part of Letters Patent No. 640,987, dated January 9, 1900.

Application filed September 1, 1899, Serial No. 729,212. (No model.)

To all whom it may concern:

Be it known that we, JAMES BAXTER and DAVID BAXTER, citizens of the United States, residing at Chicago, in the county of Cook 5 and State of Illinois, have invented certain new and useful Improvements in Filling-Machines, of which the following is a specification.

This invention relates to that class of machines used for filling cans, bottles, and the like collectively and with uniform quantities of liquids; and the object of our invention is to provide an improved and simplified machine for the purpose stated characterized by 15 valuable novel features for facilitating the filling of the machine from the reservoir quickly and without slopping or overflow, for rendering uniform and certain the discharge from the machine to the individual cans, bottles, or other receptacles, for preventing drip and waste during the interval between the withdrawal of a filled set of cans, &c., and the introduction of the next set of empty ones, and for performing other useful functions in 20 connection with the operation of a device of this character; and our invention consists in the novel means and mechanism for carrying out these functions in a practical manner, all as hereinafter fully described and claimed.

30 A machine embodying our present invention is illustrated in the accompanying drawings, in which—

Figure 1 is a side elevation of our improved filling-machine, the same being shown in position beneath a discharging spout or faucet. Fig. 2 is a front elevation of the same. Fig. 3 is a plan of the body of the machine detached from its supporting-frame. Fig. 4 is an under view of the same, showing the reciprocating valve-strips and the means for retaining them in place. Fig. 5 is an enlarged vertical transverse section on line $x' x'$ of Fig. 3, the valves being shown in their open position. Fig. 6 is an enlarged detail 40 of a stop device for limiting the movement of the valve-strips, taken on line $x^2 x^2$ of Fig. 4; and Fig. 7 is an enlarged vertical longitudinal section on line $x^3 x^3$ of Fig. 3.

Similar letters of reference refer to similar 50 parts throughout the several views.

A represents a suitable supporting-frame, which carries at its top the receiving and meas-

uring tank of the apparatus, (designated by B.) This tank B is a plain rectangular metal casting, which is divided into a series of equal-sized measuring-cells by means of longitudinal and transverse partitions b and b' , respectively. The bottom plate B' of this casting may be formed integral therewith, if desired; but to facilitate cleaning of the machine when necessary it is preferably formed separate and securely bolted thereto, as shown in Figs. 5 and 7. The partitions b and b' are cut out at their lower edges, as indicated at b^2 and b^3 , respectively, for a purpose hereinafter disclosed. In the under face of the bottom plate B' are formed a series of longitudinal grooves b^5 . These grooves correspond in number to the number of longitudinal series of cells, (four being herein shown,) each 70 groove being arranged centrally beneath one of the series. Centrally through the bottom of each cell and at the lowest point thereof is formed an aperture or port b^6 , each of these ports opening at its lower end into one 75 of the grooves b^5 , and the base or floor of each cell slopes downwardly uniformly from the line forming the base of each partition to the port in the center. Within each of the grooves b^5 is a valve-strip C, accurately and 80 snugly fitting the groove and adapted to reciprocate a short distance therein. Each valve-strip C is provided with a series of equally-spaced apertures or ports c , adapted when the valve-strip is at one limit of its 85 throw to register with the ports b^6 in the bottoms of the cells, as shown in Fig. 5. The valve-strips are secured at one end to a transverse tie-bar C', whereby they may be caused to operate in unison, and they are held snugly 90 in place within the grooves b^5 by means of a series of flat springs c' , bolted at their centers to the under face of the bottom plate B' , centrally between adjacent valve-strips C, as best shown in Figs. 4 and 5. These flat 95 springs are maintained in a position at right angles to the valve-strips against any tendency of the latter through friction to displace them from such position by pins or lugs c^2 , arranged as shown.

100 The mechanism for effecting the reciprocation of the valve-strips C comprises a rock-shaft D, mounted in bearings in brackets $d d$, secured to the front end of the casting B, a

long arm E, securely bolted to a sleeve E', rigidly secured on the shaft D, and a pair of short arms or tappets e e, keyed on the ends of said shaft and having their outer ends 5 passing through and engaging apertures c³, formed through the tie-bar C'.

To the bottom of the base-plate B' and near its front end is bolted a short forwardly-projecting plate B², Figs. 4 and 6, having an up-10 turned end B³, which is adapted to engage a set-screw C², passing through the transverse tie-bar C', to form a stop to limit the outward play of the valve-strips C. Their inward play is of course limited by the contact of the 15 inner edge of tie-bar C' against the end of the base-plate B'.

At the rear end of the machine is secured to the tank B, in any suitable manner, the overflow-basin F, provided with a spout f and 20 adapted to catch any accidental overflow of the material operated upon and carry it to the drip-bucket G.

Immediately beneath the receiving-tank and its valve mechanism is arranged a drip-25 pan, (designated as a whole by H.) This drip-pan comprises a series of gutters h, extending longitudinally of the machine and secured together in parallel relation by a skeleton framework which rests at its opposite 30 ends upon cross-bars a a on the supporting-frame A. There are as many gutters h in the drip-pan H as there are longitudinal rows of cells, and the drip-pan is adapted to be slid back and forth laterally of the machine 35 on the cross-bars a a by means of handles h' h' on opposite sides thereof, so as to bring the gutters alternately into and out of vertical alinement with the ports b⁶ and c. The gutters h all terminate at one end in a common 40 spout h² above the drip-bucket G.

Parallel with and at some distance beneath the cross-bars a a, at opposite ends of the machine, are arranged two more cross-bars a' a', each having a series of rollers a² journaled 45 therein and forming a track adapted to receive and support a box or case I, containing the cans J to be filled, said box or case being slid into position laterally from one side of the machine on the rollers a² and withdrawn, after 50 the cans have been filled, from the opposite side.

It is essential to the even and uniform filling of all the cans that the receiving-tank of the machine be maintained perfectly level, so 55 that the measuring-cells thereof will all fill equally, and to that end we equip each of the legs of the frame A with a vertical set-screw a³ at its lower end, whereby such adjustment can readily be secured in an obvious manner. 60 At K in Fig. 1 we have indicated a faucet which may tap, for instance, one of the large vats or reservoirs in a syrup or molasses factory, which vats or reservoirs contain the finished product in a heated and freely-flowing 65 state, and L indicates a cock for opening and closing the faucet.

In the operation of our improved machine

it is placed in position beneath the faucet K and then adjusted by means of the set-screws a³, so that the receiving-tank B is perfectly 70 level. This having been done and the arm E being in its raised position, Figs. 1, 2, and 7, whereby the ports b⁶ are closed by the valve-strips C, Figs. 3, 4, and 7, an attendant on the left of the machine slides into position the box or case I, containing the cans J to be filled, which cans will of course correspond in number, capacity, and arrangement within the box to the measuring-cells in the receiving-tank. Immediately after inserting 80 the case of cans in receiving position the attendant slides the drip-pan H from the position shown in full lines, Figs. 2 and 5, to the position indicated in dotted lines, same figures. A second attendant, standing in front 85 of the machine, then opens the cock L, and the hot liquid runs out into the receiving-tank A, flowing freely from cell to cell through the cut-outs b² and b³ in the walls of the cells, thus filling the cells simultaneously and more 90 quickly and with less slopping than in the old way, where all the cells, except that one directly beneath the faucet, had each to be filled in turn by the overflow from an adjacent cell or cells. When all the cells have 95 been filled just even full, the operator closes the faucet K, and then drawing the long arm E in a downward direction, as indicated by dotted lines in Fig. 7, he thereby operates the valve-strips C in a direction to cause all the 100 ports c to simultaneously register with the ports b⁶, as indicated in Fig. 5. The syrup or other liquid then flows quickly and evenly from the cells into the cans beneath, at the conclusion of which operation the arm E is 105 again actuated, this time in the opposite direction, the valve-strips C are drawn outwardly, and the ports b⁶ are all simultaneously closed. A third attendant on the opposite or 110 right-hand side of the machine then pushes the drip-pan H back into receiving position directly beneath the valve-strips C in order to catch in the gutters h any drip from the valve-strips and then withdraws from the right-hand side of the machine the case of 115 filled cans to be sealed and marked for delivery. Another case of empty cans is then slid into place by the operator on the left, and the above-described operation is thereupon 120 repeated.

It will be noticed that the ports b⁶ and c are not of uniform and equal diameter from top to bottom of their respective plates, but that they taper inwardly slightly from top to bottom. We found by experiment that where 125 these ports were simply drilled in uniform diameter from top to bottom through the base-plate B' and the valve-strips C at the instant they began to register the liquid instead of running directly downward into the 130 cans would tend to spurt sidewise to such an extent as sometimes to miss the cans altogether, thus producing a slight waste and incomplete filling of the cans. After repeated

experiments to overcome this fault we found that by tapering inwardly the sides of the apertures or ports b^6 and c uniformly from the top of b^6 to the bottom of c this tendency of 5 the liquid to spurt sidewise was entirely counteracted.

With reference to the cut-outs b^2 and b^3 in the partitions b and b' , respectively, it might perhaps seem at first thought that they would 10 tend to impair, if not to destroy, the measuring capacity of the individual cells; but where care is taken to grind the ports b^6 and c to exactly equal sizes and to perfect registration in all the cells, and where the liquid 15 operated on is properly prepared, so as to be of even and uniform consistency and viscosity, we have failed to detect in repeated experiments the slightest unevenness or irregularity in the filling of the cans. On the 20 other hand, the advantages of these cut-outs in facilitating the rapid filling of the cells and obviating unnecessary overflow and waste have already been alluded to and are too obvious to need detailed explanation.

25 The function of the drip-pan H is of course to catch in the gutters h any drippings that may adhere to the valve-strips C after a set of cans has been filled and the valve-strips have been drawn to their closing position 30 and to pass such drippings off to the bucket G through a common nozzle h^2 .

While our improved machine, as hereinabove described, has been designed primarily for use in canning such manufactured products 35 as syrups and molasses, it is not limited in its use and capability to those products, but may be advantageously employed in connection with the packing of a great variety of manufactured products which are put up 40 in liquid form, as paints, oils, &c. The size of the ports b^6 and c will in each case be regulated by the consistency and viscosity of the product which is to be run through it, these 45 ports being made relatively large for a thick viscous slow-running liquid and smaller for a thin mobile freely-flowing liquid.

Having thus described our invention, what we claim as new, and desire to secure by Letters Patent, is—

50 1. In a filling-machine, the combination with a suitable supporting-frame, of a receiving-tank carried thereby, said tank being divided into a series of equal-sized measuring-cells by longitudinal and transverse partitions, said cells each having a valve-controlled port centrally located in its base and at the lowest point thereof, and the base or floor of each cell sloping downwardly and uniformly from the line forming the base of each partition to the port in the center, and each and every partition between adjacent cells having an unvalved passage-way formed along its lower edge, whereby each cell of the series is 55 at all times in free communication with all the cells by which it is bounded through said unvalved passage-ways, as and for the purpose described.

2. In a filling-machine, the combination with a suitable supporting-frame, of a receiving-tank carried thereby, said tank being divided into a series of equal-sized measuring-cells by longitudinal and transverse partitions, said cells each having a port in its base, and said tank being provided also with parallel grooves formed in the under face of its base-plate centrally beneath parallel rows of cells, into which grooves the ports of the cells open, a series of ported valve-strips adapted to reciprocate in said grooves to control the opening and closing of the ports of the cells, 70 a series of flat springs bolted at their centers to the under face of the base-plate centrally between adjacent valve-strips and bearing at their ends against said valve-strips to hold them firmly to their seats in the grooves, said flat springs forming the only support of said valve-strips, and means for effecting the simultaneous reciprocation of the valve-strips, 75 substantially as described.

3. In a filling-machine, the combination with a suitable supporting-frame, of a receiving-tank carried thereby, said tank being divided into a series of equal-sized measuring-cells by longitudinal and transverse partitions, said cells each having a port in its base, 90 and said tank being provided also with parallel grooves formed in the under face of its base-plate centrally beneath parallel rows of cells, into which grooves the ports of the cells open, a series of ported valve-strips adapted to reciprocate in said grooves to control the opening and closing of the ports of the cells, 95 a series of flat springs bolted at their centers to the under face of the base-plate centrally between adjacent valve-strips and bearing at their ends against said valve-strips to hold them firmly to their seats in the grooves, said flat springs forming the only support of said valve-strips, means for retaining said flat springs in a position at right angles to said valve-strips against any tendency of the latter through friction to displace them from 100 such position, and means for effecting the simultaneous reciprocation of the valve-strips, 105 substantially as described.

4. In a filling-machine, the combination with the receiving-tank divided into a series of measuring-cells, and having parallel grooves formed in the under face of its base-plate centrally beneath parallel rows of cells, 110 of a series of valve-strips adapted to reciprocate in said grooves, said cells and valve-strips being provided with ports adapted to be thrown into and out of register by the reciprocation of the valve-strips, said ports both 115 in the cells and valve-strips being formed with inwardly-tapering sides from top to bottom, as and for the purpose described.

5. In a filling-machine, the combination with the receiving-tank divided into a series of measuring-cells, and having parallel grooves formed in the under face of its base-plate centrally beneath parallel rows of cells, 120 of a series of valve-strips adapted to reciprocate 125 in said grooves, said cells and valve-strips being provided with ports adapted to be thrown into and out of register by the reciprocation of the valve-strips, said ports both in the cells and valve-strips being formed with inwardly-tapering sides from top to bottom, as and for the purpose described.

- cate in said grooves, said cells and valve-strips being provided with ports adapted to be thrown into and out of register by the reciprocation of the valve-strips, and mechanism for effecting the reciprocation of the valve-strips comprising a transverse tie-bar securing the valve-strips together at one end, a rock-shaft mounted on the head of the tank, a long arm keyed on said rock-shaft whereby the same may be rocked, and short arms or tappets also keyed on the rock-shaft and at their outer ends engaging the tie-bar through suitable apertures in the same, substantially as described.
- 15 6. In a filling-machine, the combination with a suitable supporting-frame of a receiving-tank carried thereby, said tank being divided into a series of measuring-cells arranged in parallel rows, valve mechanism arranged in the bottoms of said cells for controlling the discharge therefrom, and a skeleton drip-

pan carried by the supporting-frame immediately beneath the tank, said drip-pan comprising a series of gutters rigidly held in parallel relation and spaced apart a distance 25 corresponding to the distance between the parallel rows of valves and discharging at one end through a common nozzle, and adapted to be slid back and forth laterally in a horizontal plane alternately into and out of position to catch the drip from the valves, substantially as described.

In testimony that we claim the foregoing as our invention we hereunto sign our names, this 28th day of August, 1899, in the presence 35 of two witnesses.

JAMES BAXTER.
DAVID BAXTER.
